GAME

Myron Abner Cameron Johnson, Newark, N. J.

Application March 23, 1937, Serial No. 132,637

2 Claims. (Cl. 273--134)

This invention relates to games utilizing game pieces adapted to be moved to different positions on a playing field, the said positions being indicated by throws of dice. It is an object of the invention to provide a game representing the movement of objects over predetermined paths, the rate of progress being determined by the dice which, in themselves, determine whether or not the game pieces shall be advanced or retracted, the amount of such movement, and whether or not any movement shall be permitted.

A further object is to provide a game wherein the playing field on which the game pieces are disposed, constitutes in itself a spinner which operates with a suitably prepared base to indicate transactions to be carried out by the players at certain stages of the game.

Another object is to provide game pieces which will adhere to the playing field so as not to become dislodged therefrom during the spinning action.

Another object is to provide the playing field with certain markings for indicating flying hazards or the like to be considered in connection with the thrown dice in determining the successive plays.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred form of the invention has been shown.

In said drawings

Figure 1 is a front elevation of the game apparatus constituting the present invention.

Figure 2 is a plan view of the base portion thereof, the playing field or spinner being removed and its spindle being indicated in section.

Figure 3 is an enlarged section through a portion of the playing field and showing one type of game piece applied thereto.

Figure 4 is a similar view showing another form of game piece.

Figure 5 is a view similar to Figures 3 and 4 showing another modification.

Figure 6 is an enlarged section through a portion of the playing field or spinner showing, in diagram, electromagnetic means for holding a game piece on the playing field.

Figure 7 is a perspective view of two kinds of

dice which can be used in playing the game, these dice having displayed on the faces thereof symbols indicating "visibility" and "ceiling" respectively for use in determining the advisability of moving the game pieces.

Figure 8 is a perspective view of ordinary dice used in playing the game.

Figure 9 is a view in diagram showing the sides of another form of dice which can be used for indicating direction and velocity of wind.

Figure 10 is a perspective view of one of the chips used in the game.

Referring to the figures by characters of reference 1 designates a base which can be of any desired size and proportions and is provided with an upwardly extending bearing portion 2 which can be dome-shaped, as shown, or of any other design. Extending from this bearing to the margin of the base are dividing lines 3 separating the base into different areas or segments each containing display matter representing some business or product. If desired these spaces can be used for advertising the enterprises or products displayed. Each of the spaces is provided with a designating number as indicated at 5 and is also provided with printed instructions as shown at 6 which are in the nature of orders to the player and are to be observed in the course of the game. Pins 7 are extended from the marginal portion of the bearing 2 and are located where they will 30 overlie the respective lines 3.

Projecting upwardly from the center of the bearing 2 is a stationary spindle 8 on which a sphere 9 is mounted for rotation. This sphere or globe bears a map of the world on its outer surface and has a resilient pointer or index 10 extending therefrom at such an angle that the free end thereof will successively contact with and snap past the pins 7 when the globe is rotated on its spindle.

The globe can be retained on the spindle 8 by any suitable means such as a removable ornament 11 engaging the upper end of the spindle.

In addition to displaying a map of the world, the globe can also be provided with a weather map, the isobars and other lines of the map being indicated generally at 12.

In the game illustrated there are shown four routes of travel which extend around the globe without crossing, each route being designated by 50 a series of regularly spaced apertures 13, there being the same number of these apertures along each route. At those points where it would be possible in practice to start trips by airplane around the world, special indications have been 55

provided, such as circles extending around apertures or dots as shown at 14.

If the game pieces used are to represent airplanes, they can be made up of small pieces of metal or the like cut-out to represent airplanes. These have been indicated at 15. To the back of each game piece is secured a resilient attaching device comprising opposed fingers 16 having offset terminals 17 which are rounded toward each other at their free ends. Therefore when one of these fastening devices is placed over an aperture 13 and pressed against the globe, the terminals 17 will contract toward each other and enter the aperture. Their frictional engagement with opposed portions of the wall of the aperture will be sufficient to hold the game piece 15 properly in the position where it was placed. It is to be understood, however, that instead of mounting the game pieces as described, the structure can be modified as illustrated for example in Figures 4, 5 and 6. In the structure shown in Figure 4 the globe is made of iron or other metal which will attract a magnet and this globe is adapted to be engaged by and to hold a horseshoe magnet 19 secured to and extending from a game piece 20. Obviously, therefore, the game pieces can be placed at any point desired and the magnets will adhere to the globe until they are forcibly removed. When magnets are employed the globe can be provided with perforations as already described or, if preferred, can be made without the perforations and dots can be substituted for the apertures.

In the structure shown in Figure 5 each game piece 21 has a suction cup 22 attached to it and is adapted to be pressed against the surface of the globe 23. Where suction cups are used it is advisable not to employ apertures in the globe but, instead, to utilize an imperforate globe. With this modified structure the game pieces can be placed wherever desired and the suction cups will hold them at the point where they are applied.

In the structure illustrated in Figure 6 electromagnetic means indicated generally at 24 can be located inside of the globe so that when the game pieces 25, which have flaps 26 of iron or the like on their back faces, are placed against the outer surface of the globe, the electromagnetic force will serve to hold them to the globe in the positions where they were applied. Obviously various other means than those disclosed might be used for mounting the game pieces detachably on the outer surface of the globe at any selected point.

In addition to the game pieces it is necessary, when playing this game, to utilize sets of dice. One of these dice, as indicated at 27 in Figure 7, is adapted to have displayed on its several faces, recognized symbols for indicating "ceiling." Another dice, such as 28, may have displayed on its faces symbols indicating "visibility." Another, such as the one shown in diagram in Figure 9, can indicate the velocity and direction of the wind. Obviously other dice can also be used for indicating temperatures, dew point, barometer readings, etc. In addition to these dice which indicate atmospheric conditions, etc., it is necessary to use ordinary dice such as shown in Figure 8 for the purpose of indicating the extent of movement of each game piece following each throw of the dice.

Chips of different colors are used in playing the game and one of these has been shown in Figure 10. It is also intended to use script money of different denominations.

While the game herein described can be played according to different rules and with game pieces differing from those shown and described, there has been illustrated in the present instance a game designed to represent a race around the world by airplane.

Before the starter play each player is given a predetermined amount in script money and a similar amount is placed in a "bank" from which the players draw for carrying cargo around the globe. Each player selects one of the colored chips and is given a predetermined number of them, preferably twelve. The dice shown in Figure 8 are then thrown and the player who gets the highest number begins the game by again throwing the dice to select the trading company or product to be represented by him. These companies or products are indicated in the several spaces 3 and if the player should throw a "6" and a "4" with the dice, he may select either the company No. 4, or the company No. 6, or the company No. 10, which is the total of the two numbers thrown. He then places one of his colored disks in the space representing that company. The other players proceed in the same way until a trading company has been assigned to each.

Following the foregoing procedure the No. 1 player throws the regular dice in an effort to obtain a number designated by the rules or previously determined upon by the players. If he is unsuccessful in obtaining this number the next player also throws and this procedure is continued. When each player throws the predetermined number he is permitted to start his game piece in motion and he places it on the playing field, counting out along the dots or apertures from his starting point the number of spaces or dots indicated by his throw. Some of these dots or points on the globe can be of a color differing from the others so that should the game piece land exactly on that particular dot or mark, the first player can collect a certain sum of money from the bank for carrying cargo. These specially colored points on the globe are arranged at terminal cities and represent airports where cargo is landed and picked up.

The weather indicating dice are not used until after the player is successful in getting his game piece started on the chosen route. When each subsequent play is made by each player it will be necessary for him to throw a weather dice as well as the regular dice simultaneously and if the symbol displayed on the weather dice is such as to indicate weather permitting flying, the player moves his game piece the number of points indicated by the regular dice. However if the indicated weather is not flyable, the player must spin the globe and is not permitted to advance the game piece. Instead he must carry out the instructions indicated at the place where the pointer 10 comes to a stop. If following out the instructions contained at the points indicated, any player "goes broke," it is necessary for him to sell at auction to the highest bidder any of the companies that he may own in order to secure funds to pay his obligations. The player making the purchase removes the colored marker previously laid thereon and substitutes a marker or chip of his own color in order to identify ownership. After the player becomes "broke" and has no remaining companies to sell at auction, he is forced from the game and the winner of the game is the player who is successful in winning possession of all the trading companies represented on the board.

As before stated each of the routes around the globe has exactly the same number of marked points in the nature of openings or dots. In practice it is preferred to provide red colored dots at every five points to assist the player in counting the dots while making regular moves.

Those points which can be selected by the players as starting points can be designated by circles extending around the dots or apertures as shown.

The player who is first successful in completing a round trip, landing at the starting position by an exact roll of the dice, collects a predetermined amount from all of the other players as a bonus for good navigation, etc.

It is to be understood of course that this game can be played with game pieces representing airplanes, zeppelins, boats, automobiles, etc. For example motor vehicles could be used for travelling over land and boats for travelling over water. Other game pieces can be brought into play on land to carry out battle formations, etc.

While the indicator or pointer 10 has been shown extended from the globe, it is to be understood that this position could be reversed. The pins shown at 7 on the base could be applied to the globe and the indicator could be extended from the base and the same results would be obtained. This reversible part is so obvious that detailed illustration thereof is not deemed necessary.

Instead of utilizing a globe carrying a map of the world, a sphere could be used covered with some other display matter such as a race-track, etc.

In addition to playing hazards such as indicated by isobars and by the dice, different altitudes can be located along the routes, as at 29, each altitude being indicated by numbers as "3000 feet," "4000 feet," etc. Should a game piece be brought to position at one of these points it cannot advance until the player, in his regular turn, throws the dice to indicate, in thousands, a number equal to or greater than the elevation to be surmounted.

What is claimed is:

1. A racing game including a spinner having

separate routes of travel indicated thereon and extending therearound, said routes being divided into an equal number of spaces, a detachable game piece for each route, means for holding the game pieces to the spinner when rotated, a set of dice to be thrown simultaneously having means on one for determining the number of spaces to be moved by each game piece when played and the other dice having means for indicating flying and non-flying weather conditions to be considered by the player before moving a game piece the number of spaces indicated by the first named die, said spinner being mounted for rotation when a game piece is not moved because of indicated non-flying weather conditions, an indicator on the spinner, and a stationary base having separate means thereon cooperating with the indicator for designating transactions to be performed by the player solely when advancement of the game piece is halted by weather conditions.

2. A racing game including a spherical spinner having a map of the world on its surface and hazard-indicating means on the map, there being separate routes of travel displayed on the map and extending around the spinner and across the hazards, said routes being divided into an equal number of spaces, a detachable game piece applicable to the spinner on each route, means for holding the game pieces against movement away from the spinner by centrifugal force when rotated, a set of dice to be thrown simultaneously, one die of each set having means for determining the number of spaces to be moved by a game piece when played and another die having means thereon for indicating different flying and non-flying weather conditions to be considered by the player before moving over the spaces indicated by the first named die, said spinner being mounted for rotation when a game piece is not moved because of indicated non-flying weather conditions, a pointer extending from the spinner, and a stationary base having separate means thereon cooperating with the indicator for designating transactions to be performed by the player when advancement of the game piece is halted by indicated weather conditions.
